UNITED STATES PATENT OFFICE.

DON N. THOMPSON, OF SYRACUSE, NEW YORK, ASSIGNOR TO PASS & SEYMOUR INC.,
OF SOLVAY, NEW YORK, A CORPORATION OF NEW YORK.

ELECTRIC-LAMP SOCKET.

Application filed July 23, 1920. Serial No. 398,511.

This invention relates to lamp sockets having intermediate pieces or blocks of insulation interposed between the opposing heads or buttons of insulation, which pieces 5 or blocks support the switch mechanism; and the invention has for its object a lamp socket in which the intermediate pieces or blocks of insulation are relieved of the duty of supporting the heads or buttons in spaced apart 10 relation and are protected against breakage, and in which variations in their lengths and troubles due to variations, due to firing of the blocks of insulation or porcelain, are of no consequence. 15 The invention consists in the novel features and in the combinations and constructions hereinafter set forth and claimed.

In describing this invention, reference is had to the accompanying drawings, in which 20 like characters designate corresponding parts in all the views.

Figure 1 is an elevation of a preferable form of this invention, the same being shown as a pull chain, candle socket, the contiguous 25 part of a candelabra being shown in section.

Figure 2 is an enlarged sectional view through the lamp socket.

Figures 3 and 4, (Sheet 1) are inner face views of the opposing heads or buttons of 30 the body of the lamp socket.

Figures 5 and 6 (Sheet 2) are outer and inner face views respectively, of one of the intermediate blocks, one of the metal uprights being shown in Fig. 6.

Figure 7 is a detail view of one of the 35 metal uprights.

This lamp socket comprises a body including opposing heads or buttons, means for supporting the heads and holding them in 40 spaced apart relation, and switch supporting means of insulation interposed between the heads and supported by the former means, whereby the switch supporting means of insulation is relieved of supporting the heads 45 and whereby variations therein are unimportant.

1 and 2 designate the opposing heads or buttons, these heads being usually discoidal in form and formed of suitable insulation, 50 usually porcelain.

The means for supporting the heads 1 and 2 in spaced apart relation and relieving the intermediate piece or pieces of insulation of such duty and strain, comprises a metal 55 frame preferably including two opposing

elements 3, 4, which for convenience are referred to herein as uprights, as they stand upright when the lamp socket is used as shown, in a candelabra. Each upright 3 or 4, is shown as formed with inturned feet 5, 6, at its upper and lower ends which lie in recesses in the opposing or inner faces of heads 1, 2, and which are secured to the heads by suitable screws 7, 8. 60

The switch supporting means of insulation comprises opposing elongated blocks 9, 10, of insulation interposed between the heads, 1, 2, but supported by the uprights 3, 4, the blocks being spaced apart to provide space for the switch mechanism, and to 65 permit access to such mechanism. These blocks are part-cylindrical, or segments of a cylinder, and their cylindric faces are substantially flush with the peripheries of the heads 1, 2. These blocks are also preferably 70 formed with lengthwise peripheral grooves or recesses 11 in which the uprights lie, this feature facilitating the holding of the blocks rigid with the uprights. The blocks are 75 additionally secured to the uprights by screws 80 12 extending transversely through the blocks and the uprights.

The heads 1, 2, and blocks 9, 10, interfit or lap at the ends of the blocks and as here shown, the heads are formed with projections or tongues 13, 14 extending between the end portions of the blocks. 85

The uprights 3, 4 are provided with wire terminals or binding devices as screws 15 near their lower ends and one of these uprights 3, is electrically connected to the outer lamp terminal or shell 16 by the screw 7. The central lamp terminal 17 is electrically connected in any well known manner to a conductor 18 located on the inner side of the 90 head 1 and connected to a switch contact 19 on the inner side of the block 10 between the blocks 9, 10. The upright 3 is electrically connected to a switch contact 19 by the screw 12 which mechanically secures the block 9 100 to the upright 3. This contact is mounted to the upright 3. This contact is mounted on a ratchet or cam face of a boss 20 provided on the inner face of the block 9 and includes diametrically opposite wings. The switch mechanism includes a switch arm 21 105 mounted on a shaft 22 supported at its ends by the blocks 9, 10, coaxial with the boss 20, said arm having opposite wings for engaging the wings of the contact 19, and an oscillating member 23 mounted on the shaft and 110

frame preferably including two opposing

suitably connected to the switch arm to shift it in one direction or impart an intermittent movement thereto in one direction. A spring coiled about the shaft 22 shifts the oscillating member 23 and the switch arm 21 axially on the shaft 22 toward the contact 19 and the ratchet face of the boss 20, and permits ratcheting of the switch arm 21. A pull chain 24 is connected to the member 23.

10 A quarter rotation of the switch arm, effected by a pull on the chain, turns the wings of the switch arm 21 between the wings of the contact 19, so that the switch is "off" and an additional quarter rotation 15 brings the wings of arm 21 into contact with the wings of the contact 19 and the switch into "on" position.

The switch mechanism per se, forms no part of this invention and any suitable 20 mechanism may be used in lieu thereof.

The shaft 22 extends at one end into a socket 25 in the block 4 and is provided with a square slotted head 26 at its other end, which head is exposed and accessible 25 through a work hole 27 provided in the upright 4, the upright being provided with an enlargement 28 in which the work hole is formed. The square head seats in a countersunk socket 29 at the inner end of the 30 work hole and is pressed toward its seat by a spring 30 in the socket 25. For convenience and economy in manufacture, the uprights 3, 4, are duplicates and can be made with one set of dies although it is not necessary that the upright 3 be formed with the enlargement or the work hole.

A hickey 31 of any well known construction, is mounted on the outer or lower face of the head 1, in any suitable manner and the tube 32 of the fixture is connected to the hickey. 33 is a casing enclosing the structure which casing may be of any well known or suitable construction. The feed wires are brought out of the end of the tube 32 and 45 are connected to the wire terminals on the uprights 3, 4, the ends of the wires lying in grooves 34 in the margin of the head 1. This lamp socket body, although shown as for pull chain candle sockets, for use in a 50 candelabra, obviously may be designed for use in other situations.

It is particularly advantageous in that

owing to the use of reinforcing means or uprights for the intermediate blocks of insulation, supporting the switch mechanism, 55 breakage of these blocks is prevented and lopsidedness of the body due to variations of the blocks, avoided.

What I claim is:

1. An electric lamp socket, comprising a 60 body, including opposing heads of insulation, metal uprights supporting the heads in spaced-apart relation, and being secured at their ends to the heads, blocks of insulation carried by and secured to the uprights 65 and extending lengthwise of such uprights substantially the entire distance between the heads, lamp terminals mounted on one of the heads, one lamp terminal being electrically connected to one of the uprights, a switch contact located on the inner side of said head, and the other lamp terminal being connected to such switch contact, and switch mechanism including a switch contact carried by one of the blocks and electrically connected to the other upright, and a movable switch member carried by the blocks between the same, and coacting with the switch contacts, the uprights being provided with wire terminals. 70

2. An electric lamp socket comprising a 75 body including opposing heads of insulation, metal uprights supporting the same in spaced apart relation and secured at their ends thereto, blocks of insulation carried by the uprights between the heads, lamp terminals mounted on one of the heads, one lamp terminal being electrically connected to one of the uprights, and the other lamp terminal being electrically connected to a 80 switch contact located on the inner side of said head, and switch mechanism including a switch contact carried by one of the blocks and electrically connected to the other upright and a movable switch member carried by the blocks between the same and coacting with said contacts, the uprights being formed with wire terminals, substantially as and 85 for the purpose set forth. 90

In testimony whereof, I have hereunto signed my name at Syracuse, in the county of Onondaga, and State of New York, this 24th day of June, 1920.

DON N. THOMPSON.
